UNITED STATES PATENT OFFICE.

JINDŘICH WALDES, OF PRAGUE, BOHEMIA.

DISPLAY-CARD FOR SAFETY-PINS.

1,391,287.

Specification of Letters Patent. Patented Sept. 20, 1921.

Application filed August 1, 1919. Serial No. 314,757.

To all whom it may concern:

Be it known that I, JINDŘICH WALDES, a citizen of the Czecho-Slovak Republic, residing at Prague, in Bohemia, have invented 5 certain new and useful Improvements in Display-Cards for Safety-Pins, of which the following is a specification.

My invention relates to a card for safety pins and has for its object to provide a card 10 to which the pins are secured without the pin being passed through the card, as has heretofore been the usual method.

A further object of my invention is to provide a card which may be conveniently 15 folded whereby the pins may not become loosened while they are being packed, transported or otherwise handled.

According to my invention, the card is provided with a plurality of cuts or slits, 20 the slits being arranged in pairs, a pair of slits being provided for each pin on the card. The cuts are so arranged that the ends of each pair of cuts converge, thus making the portion of the card between each pair of 25 cuts relatively narrow at its ends and relatively wide at the middle. This portion of the card is then pushed out of the plane of the card between the wires of the safety pin, the edges of the portion between the cuts at 30 the middle thereof extending over the wires of the pin.

In order to make a convenient pack, the pins may be so placed on a card that the card may be folded to inclose the pins where- 35 by the pins may be less liable to be pulled off by accident or the holding devices become torn.

My invention may be more fully described in connection with the accompanying draw- 40 ings, in which:

Figure 1 is a plan view showing a card having some of the pins in position.

Fig. 2 is a view partly in section and partly in elevation, on the line 2-2 of Fig. 1.

Fig. 3 is an enlarged section through the card showing two pin holding portions, one before being used and the other with the pin in position.

Fig. 4 shows a plan view of a card ar- 50 ranged to be folded.

Fig. 5 shows a card as shown in Fig. 4 partly folded.

Fig. 6 shows the completed package.

In the drawings A indicates a suitable 55 card having cuts or slits 5 therein, the slits

being arranged in pairs to form pin holding portions 6 therebetween. These slits 5 have their ends converging and are preferably in the shape of an arc, as shown in the drawings. By reason of the slits in each pair converging at each end, the pin holding portions 6 are comparatively wide in the middle but taper toward each end to form a comparatively narrow neck portion 7. These pin holding portions 6 are just as wide as, 60 or slightly wider than the width of the safety pins 8 with which they are adapted to be used, as shown in Fig. 3. As illustrated in Fig. 4 the size of the pin holding portions may be varied in order to secure pins of dif- 65 ferent sizes to the cards.

After the cards have been cut, as hereinbefore described, the safety pins 8, which are of ordinary construction having the usual substantially parallel wires are positioned on the cards and the pin holding portions 6 are pushed out of the plane of the cards, passing between the wires of the pins until the edges snap over the wires, by reason of the resiliency of the paper. The 70 carding of the pins is preferably accomplished by a machine for this purpose, the machine forming no part of the present invention.

The pins may be readily removed by 75 merely pulling them from the card, thereby bending the edges of the portion 6 inwardly as indicated in dotted lines in Fig. 3. The same result may be readily accomplished by pushing the portion 6 with the finger forcing it back toward the plane of the card.

In order to provide a convenient package for pins carded in this manner, I may so arrange them on the card that it may be folded to completely inclose the pins where- 80 by they are prevented from becoming loosened or detached in handling, and the pin holding portions of the cards become torn. Such a card is shown in Figs. 4, 5 and 6, in which the card A is divided into four sub- 85 stantially equal sections 11, 12, 13 and 14, the sections being formed on the creases a-a, b-b, c-c. The two end sections 11 and 12 are cut in the manner hereinbefore described to form pin holding means and 90 the pins 8 are secured thereto. The tongue 16 is cut out of the section 11, the tongue being a part of section 13. A slot 17 is cut along the crease c-c. The end sections 11 and 12 are first folded 95

110

inwardly over sections 13 and 14, respectively, as shown in Fig. 5. In this position, the safety pins are turned inwardly against the sections 13 and 14, thereby protecting 5 the pin holding portions 6, as well as the pins 8. The card is folded again along the crease $a-a$ to bring the two back faces of sections 11 and 12 together, the sections 13 and 14 forming the outside of the package. 10 The tongue 16 may then be inserted into slot 17 and the package thus held in folded position. When the package is so folded no parts of the pins are exposed. Also, in view of the fact that the pins on the sections 11 15 and 12 all lie on the surface of the card and do not pierce the card at any point, the back faces of sections 11 and 12, when folded together, as shown in Fig. 6, present surfaces opposite each other which are free of any 20 projections that might tend to catch and tear the card when the package is unfolded. It will be observed that the manner in which the slits are formed in the card provide a pin holding device between each pair 25 of slits which is formed from the card. Each pin holding device comprises two lips adapted to engage the sides of a safety pin. It will also be observed that preferably curved slits are employed but in any event 30 the opposite ends of the pin holding device between the extreme ends of the slits are narrow while those portions of the device between middle portions of the slits are rela-

tively wide, and in this way pin engaging lips are produced.

Pins secured to the cards in accordance with my invention are always held flat on the card, whereas, in the previous manner of securing the pins by passing the wire pin portion through the card, the pins were not necessarily held flat, but were free to lie in any position they might assume. My card also exhibits the pins to better advantage, in that only a very small portion of them is concealed by the cardboard.

45

What I claim as my invention is:

1. A safety pin card having slits therein arranged in pairs converging at opposite ends forming a pin holding device between each pair of slits which is narrow at each 50 end and relatively wide in its middle portion, and which is of greater length than width, thus comprising two lips for engaging the pin.

2. A safety pin card having curved slits 55 therein arranged in pairs and forming a pin holding device between each pair of slits, the slits of each pair being cut to converge at each end and thus provide a pin holding device having pin engaging lips which are 60 narrow at their opposite ends and relatively wide in their middle portions.

In testimony whereof, I have hereunto subscribed my name.

JINDRICH WALDES.
